PNEUMATIC HORN

Ellis E. Hewitt, Edgewood, Pa., and Carlton D. Stewart, Berkeley, Calif., assignors to The Westinghouse Air Brake Company, Wilmerding, Pa., a corporation of Pennsylvania

Application July 23, 1932. Serial No. 624,285

19 Claims. (Cl. 116—142)

This invention relates to pneumatic horns and more particularly to a sound producing device in which the vibration of a diaphragm is produced by creating a partial vacuum on one side of the diaphragm and in which a valve is operated by the diaphragm to connect the partial vacuum side of the diaphragm to the atmosphere.

An object of the invention is to provide a pneumatic signal horn of the above type in which 10 certain new and useful improvements in construction and arrangement of parts combine to produce a compact device which may be manufactured at a comparatively low cost.

Another object of the invention is to provide 15 a pneumatic signal horn having the above noted characteristics in which the tone adjustment means is operable from the exterior of the horn.

Another object of the invention is to provide 20 a pneumatic signal horn wherein the diaphragm and valve are readily accessible for repair or replacement without necessitating complete dismantling of the device.

A further object of the invention is to provide 25 a sound producing device of the above type in which means are provided for limiting the vibratory movement of the disc valve so as to avoid undue strain on the valve.

Other objects and advantages will appear in 30 the following more detailed description of the invention.

In the accompanying drawing; Fig. 1 is a sectional view of the sound producing device embodying our invention, associated with the intake manifold of an internal combustion engine 35 and a storage reservoir; Fig. 2 is a view, partly in section, of the disc valve and stem assembly; and Fig. 3 is an enlarged sectional view showing the normal relationship between the valve 40 for controlling the operation of the horn and the electro-magnet for controlling the operation of the valve.

As shown in the drawing, the signal horn may 45 comprise a casing 1 having a pair of chambers 2 and 3, each having a reduced bore 5, in the outer end of which is secured one end of the sections of tubing 6 which are adapted to receive and retain one end of the usual sound amplifying horn tubes 7 for the purpose of reinforcing said horn, the horn tubes 7 being preferably of unequal lengths so as to produce tones of different pitches.

Each of the chambers 5 have an annular shoulder 8 to provide a seat for a peripheral flange 9 of the sound producing mechanism, 50 which will now be described.

The sound producing mechanism comprises an open ended member 10 in which the end openings are concentrically disposed and having at one end an annular valve seat 11 and at the other end the peripheral flange 9. Adjacent the outer face of the flange 9 is a flexible diaphragm 12 of substantially the same diameter as the outer edge of the flange 9.

The diaphragm 12 is provided with an adjusting mechanism, for a purpose which will be hereinafter described, which comprises a member 13 rigidly secured or clamped to the diaphragm, centrally disposed thereof. In the present embodiment of the invention, said member has at one end a head portion which engages one side 65 of the diaphragm and a shank portion 14 which extends through a central opening in the diaphragm and a registering opening in a washer 15 in engagement with the other side of the diaphragm, the outer end of the shank portion 70 being peened over the washer to securely clamp the member 13 to the diaphragm.

The adjusting mechanism also comprises an adjusting member or stem 16 which has screw-threaded connection with the member 13 within 75 a central bore 17 in said member, the outer end of the stem being provided with a slot 18 for the reception of a suitable tool for turning said stem. A lock nut 19 is provided for the purpose 80 of locking the stem 16 in position.

Integral with the stem 16 and extending forwardly of the diaphragm is a body or stem portion 20 which may be larger in diameter than the stem 16 and which may have a peripheral flange 21. The outer face of the flange is cut 85 away, as indicated at 22, Fig. 2, so as to provide a central flat surface 23 of less diameter than the diameter of the flange.

Clamped to the stem 20 in engagement with the aforementioned face 23 is a thin metal disc valve 24. According to the construction, a shank portion 25 projects from the face 23 of the stem 20, centrally thereof, and extends through a central opening in the disc valve 24 and a registering hole in a washer 26, the end 90 of said shank being riveted over said washer.

The face of the washer 26 adjacent to the disc valve 24 is cut away, as indicated at 27, Fig. 2, so as to provide a central flat face 28 of less diameter than the diameter of the washer and of substantially the same diameter as the central flat face 23 on the stem 20.

It should be understood that the disc valve 105 can readily flex in either direction from its normal flat or straight position during the op-

eration of the device due to the fact that surfaces 23 and 28, between which the disc valve is clamped, are relatively small in diameter.

Pronounced steps 29 and 30 are formed between the portions 22 and 23 of the stem 20 and between the portions 27 and 28, respectively, of this washer 26, and the peripheral edge of the flange 21 and of the washer 26 form the corners 31 and 32, respectively, the purpose of which 10 will be hereinafter more fully explained.

It should here be noted that the combined weight of the parts comprising the diaphragm and valve assembly, including the diaphragm 12, the member 13, the stem 16, the washer 15, the lock nut 19, the stem 20 with its flange 21 and shank 25, the washer 26, and the disc valve 24, operates to control the period of vibration of the diaphragm and is an important factor in the operation of the horn. In order that 20 the combined weight of the parts may be of the precise amount, the form of the stem 20 may vary, in actual construction, from that shown in the drawing. Furthermore, in a multi-tone horn, such as is shown in Fig. 1, the stems 20 25 may be dissimilar in size and form so that the combined weights of the respective associated parts will be different, which will cause the period of vibration of one diaphragm to be different from the period of vibration of the other 30 diaphragm, with a resultant difference in the tones sounded by the horns.

The disc valve 24 is adapted to engage the aforementioned seat 11 provided at one end of the member 10.

35 The flange 9 of the member 10 and the peripheral edge of the diaphragm 12 are clamped between the shoulder 8 in the casing 1 and a rib 33 on a cover plate 34, with the valve seat 11 on the member 10 disposed in the chamber 5, said cover being secured to the casing in any desired manner. A suitable gasket 35 is inserted between the shoulder 8 and the flange 9 of the member 10.

It will be understood from the foregoing that 45 the sound producing mechanism may be readily removed for repair or replacement since the mechanism is assembled as a unit before being assembled in the horn and that said unit is accessible for removal merely by dismounting the 50 cover plate.

To seal the chambers 2 and 3 from the respective chambers 5, an annular gasket 36 is provided between the wall of the member 10 and the casing 1.

55 A chamber 37 is formed in the bore of each member 10 by the closing off of one end by the diaphragm 12, said chamber being connected to the respective chambers 2 and 3 by means of an opening 38 in the wall of said member.

60 Within the confines of each rib 33 in the cover plate 34 is a depressed portion to provide a shallow chamber 39 adjacent to each diaphragm 12.

To provide easy access to the adjusting mechanism, a hole is provided in the cover plate central with each said adjusting mechanism, said hole being adapted to be closed by a plug 40, preferably of soft rubber, which may be snapped into position and which is, of course, 70 readily removable. A port 41 is provided in each plug, so that the chambers 39 at the outer face of the diaphragms 12 remain at atmospheric pressure at all times.

75 For controlling the operation of the horn, a valve 42 is provided, the operation of which is

controlled by an electro-magnet which comprises a casing 43 having screw-threaded connection with the casing 1 within the bore 44 which may be disposed on the forward face of the casing 1 and between the horn tubes 7. The electro-magnet also comprises a winding 45, a spool 46 and a core 47, the end of the core being spaced from a lug 48 on the outer face of the valve 42.

The lug 48 and an adjacent portion of the outer face of the valve 42 is provided with a non-magnetic cover 62, as shown in enlarged section in Fig. 3, for the purpose of preventing any residual magnetism from unintentionally maintaining the valve in open position. In the present embodiment of the invention, this cover is in the form of a thin brass plate which is adapted to fit over the lug 48 and which is secured to the lug by bending over and then under an enlarged portion 49 of the lug.

80 The valve 42 is normally held seated on a seat 50 provided in the casing 1 by a spring 51 interposed between the valve and the spool 46, thereby closing off communication between the passages 63 and 52 leading to the chambers 2 and 3, respectively, and a passage 53 which is connected to a source of vacuum.

85 As shown in Fig. 1, the passage 53 may be connected to the intake manifold 54 of an internal combustion engine through a pipe 55 and to a storage reservoir 56 through a pipe 57, the latter connection being provided so as to ensure a vacuum source at all times, regardless of whether or not the engine is running.

90 A check valve 58 is interposed in the pipe 55, which is adapted to permit flow in the direction of the arrow, but prevents flow in the opposite direction, so that the vacuum accumulated in the reservoir 56 will not be lost by the flow of fluid from the intake manifold to the reservoir.

95 Of the two circuit wires 59 for the magnet, one may lead to the usual push-button (not shown), for operating the horn and the other may lead either to said push-button or to the ground, depending upon the type of circuit employed on the vehicle.

100 For the purpose of protecting the electro-magnet against the entrance of moisture, a cover 60, preferably of soft rubber, is provided, which is adapted to fit over the end of the casing 43 and is provided with an opening 61 for the reception of the circuit wires.

105 In operation, the electro-magnet is normally deenergized, so that the valve 42 will be held against its seat 50 by the spring 51. The chambers 37 and the chambers 39 at opposite sides of the diaphragms 12 are then at atmospheric pressure, and the valve 24 may just touch the seat 11 or may even be slightly away from the seat.

110 A partial vacuum is created in the reservoir 56 by the running of the internal combustion engine, which creates a partial vacuum in the intake manifold in the usual manner.

115 When it is desired to operate the horn, the electro-magnet is energized in the usual manner and the magnetic pull of the magnet will unseat the valve 42 against the light pressure of the spring 51 and the partial vacuum in the passage 53, thereby opening communication between the passage 53 leading to the source of vacuum and the passages 63 and 52 leading to the chambers 2 and 3. Inasmuch as the chambers 2 and 3 are connected through the

openings 38 to the respective chambers 37, a partial vacuum is created in the chambers 37, causing the thin flexible disc valves 24 to tightly engage the seats 11, by the action of the atmospheric pressure which acts on the outer face of the valves and even if the disc valves be slightly away from the seats, the discs will be flexed so as to tightly engage the seats.

The atmospheric pressure in chambers 39 moves the diaphragms 12 toward the left hand against the reduced pressure in the chambers 37 and with them the valve stems 20. The disc valves 24, being of thin flexible material, tend to hold to their seats and flex during the slight initial movement of the stem 20 toward the left hand, due to the atmospheric pressure acting on the outer face of the valves against the partial vacuum in chambers 37 and then the valves are forcibly pushed from their seats so that a relatively large opening is created from chambers 37 to chambers 5 and the interior of the horn tubes 7. A sudden flow of air then takes place from the chambers 5 and the horn tubes 7 to the chambers 37, causing the quick build up of pressure in chambers 37, so that the diaphragms 12, which are now flexed out of their normal positions, move back to their original positions, aided by the spring action of the diaphragms. The disc valves 24 again seat on the seats 11, so as to cut off the inflow of air to the chambers 37 and then a partial vacuum is again created in chambers 37, so that the diaphragms 12 again move toward the left hand, in the manner previously described.

35 The diaphragms 12 are thus caused to vibrate, and by the opening and closing of the valves 24, the air column in the horn tubes 7 is caused to pulsate and thus produce a sound. Because of the difference in the period of vibration of the two diaphragms due to the difference in weight of the diaphragm and valve assembly, as hereinbefore mentioned, and the difference in the length of the horn tubes, sounds of different tones are produced. By reason of the aforementioned adjustment means, the sound producing mechanism may be adjusted to produce harmonious tones pleasing to the ear.

It will be understood that, by reason of the adjustment means, the sound producing mechanism may be caused to operate satisfactorily, regardless of variations in manufacture and regardless of physical changes which the sounding mechanism may undergo in service, which would affect the position of the valve relative to its seat.

It is desirable to provide means for limiting the degree of flexure of the disc valve 24 so that the valve will not be subject to undue strain. This is accomplished by providing the aforementioned peripheral edge 31 on the flange 21 on the stem 20 and the peripheral edge 32 on the washer 26. When the disc valve is flexed in the one direction, it will engage the edge 31, and when it is flexed in the other direction, it will engage the edge 32. The degree of flexure is thus limited to a small amount so that the elastic limit of the disc valve will not be reached.

It is apparent from the foregoing that the construction of the horn is simple, that the sound producing mechanism may be readily assembled in and removed from the horn and that the adjusting mechanism is easily accessible from the exterior of the horn casing. It is also apparent that the disc valve will remain in operative condition over a long period of time due

to the means provided for protecting said valve against undue strain.

While one illustrative embodiment of the invention has been described in detail, it is not our intention to limit its scope to that embodiment or otherwise than by the terms of the appended claims.

Having now described our invention, what we claim as new and desire to secure by Letters Patent, is:

1. A sound producing device comprising a casing, a flexible diaphragm mounted in said casing, a thin disc valve operated by said diaphragm, a stem secured to said diaphragm and carrying at its outer end said valve, the portion of said stem engaging said valve having a surface of relatively small area and a surface of greater area spaced slightly from said valve when said valve is in its normal position, a washer disposed on the side of said valve opposite to said surfaces on the stem, said washer having a surface of relatively small area engaging said valve and a surface of greater area spaced slightly from said valve when said valve is in its normal position, and means for rigidly securing said washer and said valve to said stem, comprising a headed shank projecting forwardly from the stem and passing through an opening in the valve and an opening in the washer.

2. A sound producing device comprising a casing, a flexible diaphragm mounted in said casing, a thin disc valve operated by said diaphragm, a stem secured to said diaphragm and carrying at its outer end said valve, the portion of said stem engaging said valve having a surface of relatively small area and a surface of greater area spaced slightly from said valve when said valve is in its normal position, a washer disposed on the side of said valve opposite to said surfaces on the stem, said washer having a surface of relatively small area engaging said valve and a surface of greater area spaced slightly from said valve when said valve is in its normal position, and means for rigidly securing said washer and said valve to said stem.

3. A sound producing device comprising a casing, a flexible diaphragm mounted in said casing, a thin disc valve operated by said diaphragm for varying the fluid pressure on said diaphragm, a stem carried by said diaphragm to which the valve is screwed, and means on said stem for engaging said valve upon a predetermined flexing thereon.

4. A sound producing device comprising a casing, a flexible diaphragm mounted in said casing, a thin disc valve operated by said diaphragm for varying the fluid pressure on said diaphragm, a stem carried by said diaphragm to which the valve is screwed, and annular flanges carried by said stem and spaced from said valve for engaging said valve upon a predetermined flexing of the valve in either direction.

5. A sound producing device operable by fluid pressure, comprising a thin flexible disc valve, a stem to which said valve is screwed, and means for modifying the flexing of said valve, comprising members carried by said stem and spaced from said valve for engaging said valve upon a predetermined flexing movement of the valve.

6. A sound producing device operable by fluid pressure, comprising a diaphragm, a stem secured to said diaphragm, a valve seat, a valve mounted on the other end of said stem and movable into and out of engagement with said seat by said diaphragm, and means cooperating with

- in said chamber through one of the open ends comprising a hollow member, a valve seat on said member, a valve adapted to engage said seat, a cover for clamping said hollow member to said casing, and an annular gasket in sealing engagement with said member and casing. 80
18. In a sound producing device, the combination with a casing, of a sound producing mechanism in said casing, said mechanism comprising a stationary element and a flexible diaphragm defining a chamber adapted to be connected to a source of partial vacuum, a valve seat on said element, a valve operable by said diaphragm into and out of engagement with said seat for controlling a communication from the atmosphere to said chamber, a cover secured to said casing clamping said mechanism to said casing, and a gasket cooperating with said element and casing for preventing the leakage of fluid from the atmosphere to said chamber and source of vacuum exteriorly of said element. 90
19. In a sound producing device, the combina- 95
